UNITED STATES PATENT OFFICE.

HARALD F. L. STARCKE, OF PARIS, FRANCE.

MANUFACTURING AND DECORATING ARTISTIC ARTICLES.

SPECIFICATION forming part of Letters Patent No. 252,151, dated January 10, 1882.

Application filed November 1, 1881. (No model.) Patented in France September 22, 1881.

To all whom it may concern:

Be it known that I, HARALD FREDERICK LAURITZ STARCKE, of Paris, in the Republic of France, have invented a Mode for Manufacturing and Decorating Artistic Articles denominated "French Cloisonnés," (for which I have obtained Letters Patent of France for fifteen years, dated September 22, 1881;) and I do hereby declare that the following is a full and exact description thereof, reference being made to the accompanying drawings.

This invention relates to a new manner of forming polished ornaments on a base of metal, stone, or the like; and it consists in combining a metallic cellular framing with an inner ornamental filling, as hereinafter described.

Figure 1 is a plan view of a slab ornamented according to my invention. Fig. 2 is a cross-section on the line 1 2, Fig. 1.

20 *a* is a slab of slate, metal, or other material. To the face of this slab are fastened by strong adhesive cement projecting ribs *b b*, of thin metal. These ribs are first cut and bent to conform to the outlines of a picture to be reproduced, and 25 are then placed on the slab *a* to represent the positions of said outlines. The thin-metal ribs *b* form on the slab series of cells, *c d f g*, of equal depths, that are afterward filled in flush with the surface of said ribs with cements of vary-

ing colors and substances, such as marble-cement, metallic oxides, or the like. These many-colored cells produce a picture of the desired hues, that are separated by the outlines furnished by the metal plates *b*. The background *m* of the picture is also produced by filling the corresponding cells on the slab *a* with marble-cement or other cement of the proper shade. When the cement has all become dry the surface of the finished picture is polished, and may then also be glazed. Thus a rich effect is obtained by simple means.

I claim—

1. The slab *a*, combined with the projecting metallic ribs or plates *b*, forming cells, and with the filling of cement contained in said cells, substantially as specified.

2. The method herein described of ornamenting the surfaces of slabs or the like, which method consists in first attaching metallic ribs by adhesive cement to said slabs, and in then filling the spaces between said ribs flush with the outer edges thereof with colored cements, substantially as herein specified.

HARALD F. L. STARCKE.
